UNITED STATES PATENT OFFICE.

ALEXANDER H. SCHRAM, OF OREGON CITY, OREGON, ASSIGNOR OF ONE-HALF TO MARY E. MOORE, OF SAME PLACE.

DESIGN FOR A BEER-KEG GUARD.

SPECIFICATION forming part of Design No. 26,539, dated January 19, 1897.

Application filed December 11, 1896. Serial No. 615,417. Term of patent 14 years.

To all whom it may concern:

Be it known that I, ALEXANDER H. SCHRAM, a citizen of the United States, residing at Oregon City, in the county of Clackamas and State of Oregon, have invented and produced a new and original Design for a Beer-Keg Guard, of which the following is a specification, reference being had to the accompanying drawings, forming a part hereof, in which—

Figure 1 is a perspective view of a keg-guard embodying my new design, and Fig. 2 is a sectional elevation thereof.

The invention relates to guards designed

for use in tapping kegs and in disconnecting pressure-pipes, the guards serving to prevent spattering.

The leading feature of the design consists in the guard of hollow form having a neck rising therefrom at a point off the center.

I claim—

The design for a guard, herein shown and described.

ALEXANDER H. SCHRAM.
